UNITED STATES PATENT OFFICE

WILLIAM S. HAMM, OF ELKHART, INDIANA, ASSIGNOR TO THE ADLAKE COMPANY, OF CHICAGO, ILLINOIS, A CORPORATION OF ILLINOIS

DESIGN FOR A CURTAIN ROLLER END BRACKET

Application filed September 2, 1932. Serial No. 44,745. Term of patent 14 years.

To all whom it may concern:

Be it known that I, WILLIAM S. HAMM, a citizen of the United States, residing at Elkhart, in the county of Elkhart and State of Indiana, have invented a new, original, and ornamental Design for a Curtain Roller End Bracket, of which the following is a specification, reference being had to the accompanying drawing, forming a part thereof.

The curtain roller end bracket of my invention is a complete integral article of manufacture.

In the drawing,

Fig. 1 is a perspective view of a curtain roller end bracket, showing my new design; Fig. 2 is a side view of the same bracket; and

Fig. 3 is another side view of the same bracket.

What I claim is:

The ornamental design for a curtain roller end bracket, substantially as shown and described.

WILLIAM S. HAMM.
